Primary Examiner — Eric Goodman*Assistant Examiner* — Jennifer Watkins(74) *Attorney, Agent, or Firm* — Husch Blackwell LLP**CLAIM**

The ornamental design for a pouch straw, as shown and described.

DESCRIPTION

FIG. 1 is a front perspective view of a pouch straw showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines in the drawings are for the purpose of illustrating portions of the pouch straw that form no part of the claimed design.

1 Claim, 2 Drawing Sheets(56)
